CALCULATING MACHINE

Arthur J. Fettig, Detroit, Mich., assignor to Burroughs Adding Machine Company, Detroit, Mich., a corporation of Michigan

Application November 23, 1936, Serial No. 112,197

19 Claims. (Cl. 235—60)

This invention relates to a calculating machine, more particularly a multiple register machine, and is directed to the problem of controlling the register selection in relation to columnar printing.

The principal object of the invention is to provide an improved register selecting mechanism.

It is also an object of this invention to provide an improved register selecting mechanism which automatically maintains a predetermined relation between register selection and columnar printing.

Other and more particular objects of the invention will appear from the following specification and drawings which describe and illustrate one embodiment of this invention, and in which

Figure 1 is a right side elevation of a multiple register machine embodying the features of this invention and in which certain parts are cut away to more clearly illustrate the invention.

Fig. 2 is a right side elevation of a portion of the machine illustrating a rotary multiple register and certain portions of the register selecting mechanism therefor, the latter mechanism being in normal or inactive position.

Fig. 3 is a left side elevation of the portion of the machine illustrated in Fig. 2.

Fig. 4 is a right side elevation similar to Fig. 2 and illustrating the register selecting mechanism in the operative state.

Fig. 5 is a perspective view of a portion of the rotary register and associated mechanisms looking from the right side of the machine.

Fig. 6 is a front elevation of the mechanisms for moving the registers laterally out of the magazine and illustrating one register removed from the magazine.

Fig. 7 is a fragmentary perspective view of a portion of the escapement and tabulating mechanisms.

Fig. 8 is a partial front elevation of the columnar selecting or tabulating mechanism shown in position while the carriage is being tabulated.

Fig. 9 is a transverse section taken approximately along the line 9—9 of Fig. 8.

Fig. 10 is a perspective view taken from the rear right corner illustrating certain controls governing the lateral movement of the register and connections for automatically operating the machine as the register is moved into active position.

Fig. 11 is a detail of a portion of Fig. 1 illustrating the part in position with the columnar selecting key depressed and before the motor

drive has operated to cause carriage tabulation.

The invention is shown applied to a Burroughs calculating machine of the type known as a Burroughs-Moon-Hopkins Machine. The general features of this machine are shown in Hopkins patent, No. 1,336,904, and in numerous other patents covering improvements which have been made from time to time. Only such features of the machine will be described herein as are necessary for an understanding of the present invention. It is understood that, while the invention is shown as applied to a particular machine, it can also be used with other types of calculating machines.

General machine features

The machine illustrated is a combined typewriter and calculating machine of the ten key type and has ten amount keys 1 (Fig. 1), each of which operates a lever 2 to raise its index bar 3 when the key is depressed. Bars 3 index pins 4 (Fig. 6), in a traveling pin carriage 5 that is controlled by an escapement mechanism and is released one step each time a key is depressed, as shown and described in the heretofore mentioned Hopkins patent, or similar to that shown in the Thieme Patent No. 1,143,240. After an item has been indexed in the pin carriage, the machine is given a cycle of operation by hand or by motor 7 (Fig. 1), set into operation by a motor bar 8 which causes the pin carriage 5 to be raised to index corresponding pins in a stationary field of stop pins 9 (Fig. 6). These latter pins arrest the actuator racks 10, carried by arms 11 (Fig. 1), in differential positions. The actuator racks carry movable types 12 on their front ends and, after the racks have been differentially positioned, a printing mechanism is automatically operated to print the amount indexed by the racks upon paper supported by a platen P carried by a traveling paper carriage C. The actuator racks also engage and rotate register pinions as will be later described.

The keys and their connections form what may be termed amount determining devices, and the sets of index pins form indexing mechanisms. The amount determining devices together with the indexing mechanisms and the actuator racks form what may be called an amount determining differential mechanism.

Means is provided for controlling the columnar printing, that is, for causing different amounts or calculations to be printed in different columns on the paper, which in the illustrated embodiment is accomplished by controlling the travel-

ing paper carriage. This carriage C is spring urged from column to column across the machine in tabulating direction under the control of a tabulating mechanism, portions of which are shown in Figs. 7, 8, and 9. The mechanism may be the same as that described in detail in the Thieme Patent No. 1,259,929 or in the Thieme Patent No. 1,027,225. The traveling paper carriage may be automatically returned across the machine by a carriage return mechanism such as disclosed in the Thieme Patent No. 1,120,862.

A rear or main register 20 is adapted to cooperate with the actuator racks 10. This register is carried by a rockable frame which may be moved at predetermined times during cycles of operation of the machine to engage and disengage the register and the racks. The rear register and rocking frame have not been shown in detail but are described in the Hopkins patent and in the Thieme Patent No. 1,321,260, to which reference is made for a disclosure of these mechanisms.

The machine is also provided with multiple registers 21 which are movable into and out of a drum type magazine 23 and may be caused to engage and disengage the racks. These latter mechanisms have not been shown but are shown and described in the Muller Patent No. 1,920,477.

Suitable tens-transfer mechanisms are provided for each register. These mechanisms have not been illustrated in detail but are disclosed in several of the heretofore mentioned patents.

The multiple register magazine 23 is rotatably mounted at the side of the group of actuator racks 10. The magazine is normally spring urged clockwise and may be indexed in a manner similar to that shown and described in the Muller patent to bring the desired register to indexed or selected position after which the register is removed laterally from the magazine to the front register frame where it is in position for cooperation with the actuator racks. This frame is rocked to engage and disengage the register with the racks to perform the various calculating operations possible on the machine, all as described in the Muller patent.

The mounting of the multiple registers and the mechanisms for removing them from and returning them to the magazine are described in detail in the Muller Patent No. 1,920,477. Portions of these mechanisms have been illustrated herein, but no attempt will be made to describe them in detail. The manner in which the registers are combined with and are controlled by the rest of the mechanism will be later described.

The present trend and commercial practice require that machines of this type operate as quickly as possible and be absolutely error-proof. In a machine of the type illustrated in Muller Patent No. 1,920,477, wherein the carriage carries stops 30 positioned to engage pass-by pawls 31 for causing indexing of the multiple register magazine, it is sometimes desired to rotate the magazine a distance commensurate with several registers while the paper carriage travels a distance of only one column or it may be desired to tabulate the paper carriage through several columns and simultaneously rotate the register magazine through an arc containing several registers. It is necessary under these conditions to assure proper register selection in accordance with the columnar position of the paper carriage without delaying operation of the machine by slowing down the paper carriage.

The present invention provides for positive

and accurate register selection in accordance with, or synchronized with, the position of the paper carriage regardless of the distance the carriage is tabulated or the speed at which it tabulates. In other words, the present invention insures that the proper number of escapements of the magazine will take place during any tabulating movement of the paper carriage, when the paper carriage is skip-tabulated or when several escapements of the register magazine are necessary for one columnar shift of the paper carriage. In skip-tabulating difficulties may occur because after the initial inertia of the carriage in starting has been overcome the carriage travels very rapidly through the second and later columnar positions and may not consume sufficient time to permit complete escapement of the register magazine. When several register magazine escapements are necessary for one columnar tabulation it is apparent that sufficient time for several escapements of the register magazine may not be available.

Multiple register selecting

As in the Muller patent, the paper carriage is provided with the required number of register selecting dogs 25 each of which carries a pass-by pawl 26 positioned to engage the rollers 27 of an escapement wheel 28 (Fig. 5). Escapement wheel 28 is journaled on a stud 29, carried by arm 30 pivoted about a horizontal pivot 30^a (Fig. 3). Wheel 28 is formed with a bevel gear 31 which meshes with a bevel gear 32, fast on a shaft 33 which extends to the right side of the machine where it carries a gear 34. Gear 34 meshes with an idle gear 35 which in turn engages a larger gear 36, journaled on a stud 37, and having secured thereto an inner ratchet 38 engaged by a pawl 39 (Figs. 2, 4 and 9) pivoted at 40 and spring urged counter-clockwise. Pawl 39 permits only counter-clockwise rotation of gear 36 and ratchet 38. An outer larger ratchet 41 is also secured as a unit to gear 36 and ratchet 38 and is engaged by pawl 42, spring urged clockwise and having a nose 43 engaging the teeth 44 of ratchet 41. Pawl 42 is pivoted at 45 on an arm 46, also journaled on stud 37. Arm 46 is urged clockwise about stud 37 by a spring 48 (Fig. 2) until a projecting finger 47 of arm 46 engages a stud 48.

From the construction thus far described it will be seen that, as pass-by pawl 26 travels to the left in tabulating movements of the carriage, it will engage a roller 27 and rotate wheel 28 and gear 31 clockwise. This will cause counter-clockwise rotation of pinion 34 and counter-clockwise rotation of gear 36 and ratchets 38 and 41.

This movement of gear 36 and its associated ratchets permits escapement of the register magazine which is normally urged clockwise by a spring as disclosed in the Muller patent. The escapement mechanism is very similar to that disclosed in the Muller patent, but is slightly different and the differences will, therefore, be described.

The normal position of the parts just described is with the nose 43 of pawl 42 engaged in between two teeth of the ratchet 41. As the gear 36 and the two ratchet wheels 38 and 41 are rotated in unison by engagement of pass-by pawl 26 with a roller 27 of wheel 28 during carriage tabulation, pawl 39 will engage successive teeth of ratchet 38 and prevent reverse rotation of the latter. During this movement of ratchet 41, arm 46

44 will be rotated step by step in a counter-clockwise direction because of the engagement of pawl 42 with the outer ratchet 41. The parts have been so designed as to permit movement of arm 44 to the extent of three teeth on ratchet 41. This amount of permissible movement can of course be varied to suit particular requirements, but it has been found that three teeth have been sufficient for all cases arising to date. 10 In other words this permits of a lag of three steps of the register magazine for any given tabulating movement of the carriage.

Movement of arm 44 is made use of to permit escapement of the register magazine. For this purpose arm 44 is provided with a stud 50 (Figs. 2 and 4) projecting inwardly in position to engage the cam surface 51 of one arm 52 of a lever pivoted at 53 and having a forwardly extending arm 54 engageable with a stud 55 carried by one arm of the register magazine escapement pawl 56 (Fig. 4). This latter pawl is adaptable to teeth 57 in the escapement ratchet of the register magazine in a manner similar to the pawl 62 of the Muller Patent 1,920,477. Accordingly, as the arm 44 swings counter-clockwise upon counter-clockwise movement of gear 36, the stud 50 will engage the raised or high portion 51^a of the cam surface 51 of lever 52 and rock the latter clockwise, and immediately release pawl 56 to permit escapement movement of the magazine 23 in a clockwise direction as shown in Fig. 4.

Pawl 42 is provided with a stud 60 at its upper end positioned to engage an arcuate arm 61 of lever 62 fixed to shaft 63, to which is also fixed another arm 64 carrying a pivoted pawl 65 upon its outer end. Pawl 65 carries a stud 66 projecting therefrom, which engages lugs 67 of an auxiliary escapement ratchet 68 carried by the magazine, there being a lug 67 for each of the 40 register positions of the magazine. Accordingly, as ratchet 41 and pawl 42 move counter-clockwise upon carriage movement, stud 50 rocks lever 52, which in turn rocks and releases escapement pawl 56, thereby freeing the magazine for clockwise rotation under urge of its spring. As the magazine moves, a lug 67 engages stud 66, rocking arms 64 and 62 clockwise whereby arm 61 engages stud 60 and rocks pawl 42 about its pivot until the upper nose 43^a thereof engages a tooth 50 of ratchet 41. This permits pawl 42 and arm 44 to restore clockwise a distance of one-half a tooth. As lug 67 passes beyond stud 66, arm 61 moves counter-clockwise away from stud 60 and permits a lower nose 43 of pawl 42 to engage the next tooth 55 of ratchet 41, thus permitting restoration of pawl 42 and arm 44 a full tooth. If this movement of pawl 42 and arm 44 is sufficient to lower stud 50 below the high portion 51^a of lever 52, pawl 56 will engage the next tooth 60 67 of the main escapement ratchet and thereby stop escapement of the magazine. If, on the other hand, pawl 42 and arm 44 have been advanced three tooth spaces as illustrated in Figure 4, resulting from a rapid or extensive carriage movement before the magazine has had time to follow up, arm 44 and pawl 42 will receive successive movements until stud 50 reaches the lower portion of the cam surface 51. During these successive restoring movements of pawl 42 and lever 70 44 and until stud 50 travels off the high portion 51^a of cam surface 51, magazine 23 is free to escape, that is, during the aforesaid movement of pawl 42 and arm 44 escapement pawl 56 is held away from teeth 57.

75 Accordingly each time the carriage tabulates

and advances the escapement wheel, arm 44 is advanced one tooth space in a counter-clockwise direction, thereby releasing the rotary magazine to travel in a clockwise direction until the pawl together with arm 44 restores to normal position 5 and releases pawl 56 to re-engage the next tooth of the magazine ratchet.

If the paper carriage is caused to skip-tabulate through three columnar positions and a register trip dog is located in each carriage position, pawl 42 and arm 44 may be moved by the carriage a distance equal to three tooth spaces of the ratchet 41. However, as the carriage is traveling through these three columns, the magazine 23 is also escaping, with the result that 15 the pawl 42 is being released to move back to its normal position at approximately the same time that the ratchet 41 is being advanced by the carriage if the columns on the form being used are of sufficient width so that as the carriage travels through the various columns there is sufficient time for the pawl 42 and the register magazine to escape while the carriage travels through each column. Under these conditions pawl 42 will never advance beyond a single tooth 25 space from its home position. On the other hand, if the columns on the carriage or form are very narrow and the register trip dogs are spaced close together on the carriage, the ratchet wheel 41 may be advanced several steps or tooth 30 spaces before the ratchet pawl 42 and the escapement of the magazine has had time to take place. Under these conditions, it is conceivable that the pawl 42 and the arm 44 can be advanced faster in a counter-clockwise direction 35 than the escapement of the register magazine can take place in a clockwise direction. In this event, the pawl 42 will gradually be raised two or three tooth spaces away from its home position while the carriage is skip-tabulating through 40 several columns.

In actual practice, however, this seldom happens, and it has been found that a provision or allowance for a three tooth space rise of pawl 42 and arm 44 is more than necessary to take 45 care of all practical applications. Of course if the carriage becomes stationary and the register magazine has not caught up with the carriage, it will continue to escape through several register positions, and as each register position is passed, the pawl 42 is released a single tooth space until it finally restores to its normal home position as shown in Fig. 2. In Fig. 4 the pawls are shown in their maximum variance; that is, with the pawl 42 advanced three tooth spaces 50 ahead of the carriage position. From such a position the arm 44 and the arm 64 would take three movements each in order to permit the magazine to catch up with the carriage and become synchronized therewith; that is, until the pawl 42 returns to normal or home position. Of course the same action would take place if it was desired to skip several register positions between two adjacent columns of the carriage, in which case three or more carriage release dogs would 55 be placed close together within one columnar position of the carriage.

There has been provided therefore a register selecting means under control of the carriage, which means in itself comprises an escapement 70 or storing mechanism which controls the register magazine escapement mechanism. This mechanism eliminates any necessity in the present machine to retard the speed of the paper carriage in order to keep the carriage in step with the 75

register magazine, and this is true regardless of the extent or speed of tabulating movement of the paper carriage.

Interlocks

5 As in the Muller patent heretofore mentioned the register magazine is provided with twenty registers and twenty register positions, and provision is made to prevent the register from rotating beyond its twentieth position. Provision is 10 also made in the illustrated machine to prevent continued indexing of pawl 42. This is accomplished by removing the escapement wheel 28 from possible engagement with pass-by pawl 26. 15 For this purpose an arm 75 (Fig. 3) is secured to the pivot pin 30^a which carries arm 30, upon which escapement wheel 28 is mounted. Arm 75 is normally urged counter-clockwise by a spring 77 and is retained against such movement 20 by a latch crank 78, the forward end of which terminates in a hook which engages a stud 79 carried by the upper end of arm 75. Crank 78 is pivoted at 80 and its rear end has a slotted connection 81 with the forward end of a crank 25 82 journaled on stud 83 and being normally urged clockwise by a spring 84. Journaled on the same stud 83 is a three-arm lever 86 yielding- 30 connected to crank 82 by a spring 87, the relative movement of the lever 86 and crank 82 being limited by a second arm engaging a stud 88 carried by crank 82.

The third arm of the three-arm lever 86 has a square stud 89 which engages the shoulder of a pivoted lever 91 which latter lever prevents 35 clockwise rotation of the three-arm lever 86 and accordingly prevents clockwise movement of bell crank 82 which in turn prevents release of latch 78. When the register magazine reaches its twentieth register position, a stud 92 carried by the magazine engages lever 91 and rocks the latter clockwise, thus permitting clockwise movement 40 of lever 86 and crank 82 which in turn rotates crank 78 counter-clockwise. This releases arm 75 and permits spring 77 to rotate the latter 45 arm counter-clockwise to remove the escapement wheel 28 out of possible engagement with pass-by pawl 26, and thus prevents any further movement of pawl 42.

Lever 91 also has a stud and slot connection 50 93 with a link 96, the other end of which is connected to an arm 97 fast upon a shaft 98. Shaft 98 extends across the rear of the machine to the other side of the magazine, where it carries an arm 99 (Figs. 2 and 4) having a stud and fork 55 connection 100 to an arm 101, formed integrally with pawl 39. Movement of lever 91 will rock shaft 98 which in turn will rock arm 101 with pawl 39 and release the latter from ratchet 38 to permit return of arm 44 and pawl 42 if the latter 60 has, through any mismanipulation, been raised. This permits restoration of pawl 42 at the same time that register magazine 28 reaches its twentieth register position.

Therefore, if a misoperation occurs by which it 65 is attempted to index the magazine beyond its capacity of twenty registers, the present invention is disabled by the means shown and described under control of the stud 92 which causes retraction of escapement wheel 27 out of possible 70 engagement with the carriage dogs and also disables the escapement pawl 39 so that all parts will assume their normal or home positions in preparation for the starting of the new transaction, and reestablishing synchronization of the 75 register with the carriage.

It is understood, of course, that after the magazine has been moved to its No. 20 register position, where the register indexing means is automatically disabled as above described, the magazine will be restored counter-clockwise to 5 its No. 1 register position by means disclosed in the heretofore mentioned Muller patent, and the stud 92 will move away from latch or lever 91. As the magazine is restored to its No. 1 register position the stud 92 after first permitting arm 10 91 to move will engage the lower arm of the three-arm lever 86 which carries stud 89 and restore the three-arm lever and the crank 82 to initial positions. This moves bell crank 78 clockwise which because of the end cam surface 15 cams the arm 75 clockwise and relatches the latter in position with the escapement wheel 28 in enagaging relation to the dog 26.

In order to prevent the arm 44 and pawl 42 from being moved beyond the permissible three-tooth advance movement of the arm 44 in the event that through misoperation, such as continued movement of the carriage while the magazine is prevented by some means from escaping, the pawl 39 is provided with a downwardly extending arm 102 (Figs. 2 and 4) in position to be engaged by the stud 50 carried by arm 44 (Fig. 4). If the latter moves counter-clockwise beyond the permissible movement of three teeth on the ratchet 41 stud 50 will engage arm 102 and 30 rock the pawl 39 out of engagement with its ratchet 38, thus permitting clockwise movement of ratchet 38 one tooth, whereupon the stud 50 will move away from the arm 102.

Means are also provided to prevent the gear 35 38, the ratchet 38, the ratchet 41 and the arm 44 from being returned too rapidly and farther than necessary by the spring 48 when the pawl 39 is disengaged from the ratchet 38. This means comprises an arm 103 (Figs. 2 and 4) journaled 40 on stud 49 and constantly urged clockwise by a spring 104 so as to bring a stud 105 carried by the outer end of the arm into yielding contact between the teeth of the ratchet 38.

Column selecting mechanism or carriage tabulating control 45

It is obvious that the foregoing mechanisms are adaptable to machines having various types of carriage tabulating controls. For example, it is 50 adaptable to a machine having a rotary magazine exactly as shown in the Muller Patent No. 1,920,477 and is more particularly adaptable to a machine of this type where two or more register trip dogs are used within a single columnar position of the paper carriage.

The invention is also applicable to a machine of this type having a tabulating mechanism involving the general features of the Thieme Patent No. 1,027,225, slightly modified to provide 60 skip-tabulation. This is accomplished by notching the tabulator stops and the upper ends of the tabulator tips that engage the stops, whereby depression of certain tabulating keys would allow the paper carriage to pass all other tabulating 65 stops until the one came along that matched the shape of the notched tabulating stop, which would stop the carriage in that particular column.

On the other hand, the invention has been found especially well adapted to a machine as 70 shown and having the tabulating or column selecting mechanism illustrated in Figs. 1, 8, and 9. In this type of construction a series of keys are provided across the front of the carriage and each key represents a particular columnar position 75

tion of the carriage, so that when one of the keys is depressed the carriage is first caused to tabulate into the desired column and then, without attention on the part of the operator, the register which has been selected by the carriage dogs automatically moves from the magazine into active relation with the actuators and, finally, as the register moves into position, the register movement causes the motor clutch and drive to be tripped to operate the machine after the selected register is in active position. As the machine completes the stroke of operation, the active register is restored to the magazine. A subsequent depression of another one of the selecting keys repeats the above operation in the new columnar position of the carriage. It is understood, of course, that the digit keys for entering an amount must be depressed before the column selecting keys are depressed because the complete cycle of operation is entirely automatic after the column selecting key has been depressed. A more detailed explanation of this type of column selecting mechanism and the particular application of this invention thereto will now be given.

The machine is provided with a plurality of tabulating or column selecting keys 110 (Figs. 1, 8 and 9) removably and adjustably carried by a slotted shaft 111 extending across the carriage and supported at each end by an arm 112 formed integrally with the carriage. Shaft 111 is provided with a slot for each letter space position of the paper carriage, which permits adjustment of keys 110 to any letter space position of the carriage and, therefore, according to the positions of the keys 110, the carriage may be tabulated to any desired letter space position. In order that the keys may be readily removable and replaceable, they are provided upon their lower ends with a hook portion 113 which engages in the slots of shaft 111, and are retained upon the shaft by a leaf spring 114 as clearly shown in Fig. 9. The keys are rockable inwardly and when so rocked a lower foot portion 115 engages a ball 116 extending across the carriage and being pivoted to the end plates of the carriage at 117. The lower portion of the ball is adapted to engage a stud 118 carried by a slide 119, the lower end of which is pivotally connected to a lever 120 (Fig. 1) pivoted on a shaft 121. The opposite end of lever 120 is connected to one end of a link 122, the other end of which is connected to a crank 123 pivoted at 124 to the base of the machine. The rear portion of crank 123 carries a stud 125 which engages the switch 125^a controlling the motor 7 for closing the switch upon depression of any column selecting stop. The rear end of crank 123 has a slotted connection with one end of a lever 126 pivoted at 127 and carrying upon its other end a stud 128 which engages a curved arm 129 pivoted to the rear end of a slide 130.

Upon depression of a column selecting stop 110 arm 129 is lowered into position to be engaged by one of a series of studs 131 carried by a gear 132 driven from the main motor. Upon closing the motor switch 125^a, the motor is caused to rotate, whereupon a stud 131 engages arm 129 and pulls slide 130 rearwardly. The forward end of slide 130 is connected to a crank 133 also pivoted at 124 and rocks the crank counter-clockwise. The other arm of crank 133 is connected to one end of a link 134, the other end of which is connected to a lever 135 fixed to the shaft 121 and extending forwardly to where it is

secured to one end of a slide 136, the upper end of which extends through a block 137 and terminates in a tabulator stop 138.

Column selecting key 110, therefore, not only closes the motor switch but, through the elements just described, rocks shaft 121 clockwise and raises the tabulator stop 138 into position to be engaged by the depressed key 110 as illustrated by dash-dot line in Fig. 9. The tabulator stop 138 is latched in raised position by an abutment 139 carried by the stop and which overlaps the top of block 137 when the stop is raised. The slide and stop are urged to the right (Fig. 8) for this purpose by a spring 140. The stop 138 is permitted to move laterally within the block 137 and, when it is engaged by a key 110, it moves sufficiently to the left (Fig. 8) to be lowered below the top of block 137 and to disengage latch 139. The shock of this engagement is cushioned by the dashpot 141.

In order for the carriage to tabulate, the usual escapement mechanism of the carriage must, of course, be released. This escapement mechanism is illustrated briefly in Fig. 7 and comprises generally an escapement ratchet 142 on a shaft 143 which also carries the pinion 144 which engages the carriage rack 144^a. A pawl 145 engages the ratchet 142 and is mounted on the end of a link 146 which is actuated by the typewriter keys K (Fig. 1) or space bar B through the universal bail (not shown) in the usual manner to permit a latter space escapement at each typewriter key depression.

Shaft 121 (Fig. 1), which is rocked clockwise upon depression of a key 110, carries an additional arm 147 to which is pivotally connected one end of a lever 148 pivoted at 149 and attached at its rear end to a link 150. Accordingly as shaft 121 is rocked clockwise it raises link 150. Link 150 extends upwardly and engages a stepped crank 151 (Figs. 1 and 7) pivoted at 152 and engaging a stud 153 projecting from the pawl 145. An upward movement of link 150 will rock crank 151 and lower pawl 145 to release the escapement ratchet 142 and permit the carriage to tabulate. Depression of a column selector key 110, therefore, also releases the carriage escapement mechanism while it at the same time sets up a tabulating stop. Upon the lowering of the tabulator stop, caused by a tension spring 154 pulling upwardly upon the connection of arm 147 on shaft 121 with link 150, link 150 is also lowered to permit restoration of escapement pawl 145.

As the tabulator stop is restored and the lever 135 on shaft 121 (Fig. 1) is moved counterclockwise to its normal position, a hook 156, pivotally carried by lever 135 engages a stud 157 projecting from lever 120 and rocks the latter counterclockwise to restore the depressed key to normal position.

After a column selecting key 110 has been depressed and the carriage tabulated to the new selected column, a register of the register mechanism is moved laterally into active position with the actuators as follows:

It is understood that when the magazine 23 is being rotated, i. e. while a register is being selected, all of the registers are supported within the magazine, as seen in Figure 5. But after the magazine has been indexed and the paper carriage is positioned in a new column, the selected register is automatically moved from the magazine into active relation with the actuators 18, as seen in Figure 6. The register is automat-

ically moved by mechanisms very similar to those disclosed in the Muller Patent No. 1,920,-477 with certain modifications as will now be described.

5 A link 160 (Fig. 1) is connected to the rear end of lever 146 where it connects with link 160 and also to the forward end of a crank 161 (Figs. 1 and 10) pivoted at 162 and carrying a hook 163 at its rear end. When the column selecting key is depressed, hook 163 (Fig. 10) will be lowered to engage a stud 164 projecting from a slide 165, and upon return of key 110, hook 163 will raise slide 165 to release a latch 166 which, in turn, permits rotation of a three-10 armed lever 167. This lever corresponds in function to the three-armed lever 179 of the Muller Patent No. 1,920,477. As explained in this patent, lever 167 (179 in Muller) controls lateral movement of the register to and from its magazine.

15 With the carriage in its new selected column and the selected register in active relation to the actuators, the machine is automatically conditioned for operation. As described in the Muller patent, the three-armed lever 167 is moved clockwise as the register is moved laterally from the magazine, and this movement causes a stud 170 carried by the three-armed lever 167 to engage and lower a slide 171 which, in turn, rocks a pawl 172 counterclockwise to engage a stud 173 carried by a clutch lever 174 to raise the latter. The raising of clutch lever 174 releases the clutch and causes the machine to take a single stroke of operation, as disclosed in the Muller patent.

20 Thus, after the key 110 has been depressed, the carriage tabulates to the desired column, during which time, the register magazine is indexed to the selected position and after which the register is automatically moved to active position, and this movement of the register finally releases the motor clutch to cause the machine to take a stroke of operation. All of the foregoing takes place as the result of a single depression of one of the column selector keys 110.

25 During operation of the machine, an arm 176 (Fig. 10) descends and disengages hook 163 to permit restoration of the register in the magazine at the extreme end of the machine operation, as disclosed in the Muller patent.

30 As a further insurance that the register magazine will be in step or synchronism with the carriage—that is, to insure that the correct number of register escapements will take place—the magazine escapement pawl 50 is provided with a forwardly extending finger 178 (Figure 4) which, when the pawl is in clockwise or released position, occupies a position in front of the register carriage 177, so as to prevent movement of the latter.

35 Accordingly, a register cannot be moved laterally out of the magazine, even though latch 166 (Figure 10) has been released, until the magazine has been fully positioned with the proper register in position to be moved to active position. When this condition exists, pawl 50 will be in its counterclockwise position, and finger 176 will be removed from in front of the register carriage 177. Therefore the synchronizing mechanism will prevent machine operation, even though the carriage has completed its travel, if the proper register has not been selected and moved laterally into active position with the actuators.

40 The foregoing mechanism is also well adapted for vertical posting work in which the carriage remains stationary, and amounts are entered and listed or totals taken and printed in vertical order. In operations of this kind, the digit keys are first depressed to index the amount to be entered, after which the motor bar 8 is depressed. Depression of the motor bar moves a wire 180 (Figure 1) which, in turn, rocks a crank 182 counterclockwise to raise slide 165. This, as previously 45 explained, releases the selected register to move laterally into active position; and after the register has completed its movement laterally, the motor drive is tripped through the link 171.

45 It will be seen from the foregoing that the clutch is not released either from the motor bar or from the keys, but that the clutch is operated as the register moves laterally from the magazine into active position. In other words, the operation of the machine is controlled by the register, or more specifically by lateral movement of the register from its magazine. This mode of operation has certain advantages, in that the amount may first be set up on the keyboard and 50 then later, a selection of the register may be made. Furthermore, machine operation is positively prevented until the register has been completely moved to its active position with the actuators.

Power operated result keys

55 The foregoing mechanism is also employed to provide for what is sometimes termed "power operated result keys." When in a machine as disclosed in the Muller Patent 1,920,477, a result key, such as a total key is depressed the register automatically moves from the magazine into active relation with the actuator racks at the proper time. After this movement it is necessary to depress the motor bar to operate the machine. Substantially the same mechanism is employed in the present invention in which an arm 186 of bail 186 (Fig. 10) is rocked upon depression of the total key T (Fig. 1). Bail 186 is provided with a second arm 187 which underlies the lower end of slide 165 and upon rocking of bail 186 raises slide 165. This, as previously explained, releases the selected register to move into active position. The parts 185, 186 and 187 correspond to the parts 300, 301 and 302 of the Muller Patent 1,-920,477. In the present machine as previously explained, movement of the register out of the magazine into active position relatively to the racks trips the motor clutch and initiates an operation of the machine. Accordingly, we have an actual operation of the machine upon depression of a result key without the necessity of depressing the motor bar.

60 It will be apparent from the foregoing that the principal features of this invention may be applied to machines of other types than the one described and that minor changes may be made in the details of construction without departing from the spirit and scope of the invention as defined in the appended claims.

I claim:

1. A calculating machine having a traveling paper carriage, a register support, a plurality of registers on said support, and means under control of said paper carriage for indexing said register support as said carriage is moved from column to column, said means comprising an escapement mechanism conditioned by said carriage during movement thereof and operable 70

while said carriage is stationary to continue indexing of said register support.

2. A calculating machine having a travelling paper carriage, a register support, a plurality of registers on said support, means releasably holding said register support against indexing movement, and means under control of said paper carriage for operating said releasable holding means to release said register support for indexing movement as said carriage is moved from column to column, said means comprising an escapement mechanism conditioned by said carriage during movement thereof and operable while said carriage is stationary to complete indexing of said register support.

3. A calculating machine having columnar-printing control means, a register magazine, a plurality of registers in said magazine, said registers being removable from said magazine into active position, an escapement mechanism for indexing said magazine to select a predetermined register in accordance with the position of said columnar printing control means, means controlled by said escapement mechanism for moving said registers to and from said magazine, and means controlled by said last-mentioned means for preventing operation of said machine until said selected register is removed from said magazine and is in active position.

30 4. A calculating machine having a traveling paper carriage, a register support, a plurality of registers on said support, a detent for said support, a pair of ratchets, means carried by said carriage for rotating said ratchets, a pair of pawls 35 engaging said ratchets, and means associated with one of said pawls for controlling said detent.

5. A calculating machine having a travelling paper carriage, a register support, a plurality of registers on said support, a detent for said support, a pair of ratchets, means carried by said carriage for rotating said ratchets, a pair of pawls 40 engaging said ratchets, and means associated with one of said pawls for controlling said detent, one of said pawls being movable both with and relatively to its associated ratchet.

6. A calculating machine having a traveling paper carriage, a register support, a plurality of registers on said support, register selecting means controlled by said carriage for initiating indexing of said support as said carriage moves from column to column to select a predetermined register in accordance with the position of said carriage, said means being operable to complete indexing of said magazine while said carriage is stationary, and means for preventing continued operation of said means after said support has been indexed to its capacity.

7. A calculating machine having columnar-printing control means, column selecting keys for controlling said columnar-printing control means, a register support, a plurality of registers on said support, register selecting means controlled by an element of said columnar-printing control means for initiating indexing of said support to select a predetermined register in accordance with the position of said columnar printing means, said means being operable independently of columnar movement of said columnar-printing control means to complete indexing of said magazine, and means controlled by said column selecting keys for preventing operation of said machine until said support has been indexed.

75 8. A calculating machine having columnar-

printing control means, column selecting keys for controlling said columnar printing means, a register magazine, a plurality of registers in said magazine, said registers being removable from said magazine into active position, means controlled by an element of said columnar-printing control means for indexing said magazine to select a predetermined register, means controlled by said keys for moving said selected register to and from said magazine, and means for preventing operation of said machine until said selected register is removed from said magazine and is in active position.

9. In a calculating machine, power means for giving said machine cycles of operation, connections comprising a clutch for operatively connecting said power means to said machine, columnar-printing control means, column selecting keys for controlling said columnar-printing control means, a register magazine, a plurality of registers in said magazine, register selecting means controlled by an element of said columnar-printing control means for indexing said magazine as said columnar-printing control means is conditioned for printing in different columns to select a predetermined register in accordance with columnar printing, and means controlled by said keys for preventing engagement of said clutch until said magazine has been indexed.

10. In a calculating machine, power means for giving said machine cycles of operation, connections comprising a clutch for operatively connecting said power means to said machine, a traveling paper carriage, column selecting keys for controlling tabulating movements of said carriage, a register magazine, a plurality of registers in said magazine, said registers being removable from said magazine into active position, register selecting means controlled by said carriage for indexing said magazine to select a predetermined register in accordance with the position of said carriage, means controlled by said keys for moving said registers to and from said magazine, and means controlled by said keys and operated after said selected register is removed from said magazine and is in active position for causing engagement of said clutch.

11. A calculating machine having differential actuator mechanism, a plurality of registers carried by a movable register support, register selecting mechanism controlling movement of the register support to positions to select individual registers carried by said register support for cooperation with said differential actuator mechanism for performing calculating operations, a columnar-printing control means controlling said register selecting mechanism and movable to a plurality of register selecting positions, said columnar-printing control means being movable independently of said register support whereby it may move through a plurality of register selecting positions in less time than the register support moves through the like number of register selecting positions, said register selecting mechanism having a means which is controlled by both the columnar-printing control means and the register support and which, when the columnar-printing control means moves through successive register selecting positions more rapidly than the register support moves through successive register selecting positions, is conditioned in accordance with the number of register selecting positions through which the columnar-printing control means moves in excess of the number of register selecting positions through which the

register support moves, said means continuing to operate after the columnar-printing control means has stopped moving to cause the register support to continue to move until it has moved through as many register selecting positions as the columnar printing control means.

- 5 12. A calculating machine having a columnar-printing control means, amount differential actuator mechanism, a register support, a plurality of registers carried by said register support, said register support being movable to select individual registers carried by said register support for cooperation with said differential actuator mechanism for performing calculating operations, a means movable away from a normal position to cause release of said register support for movement and also movable back to said normal position to cause arrest of the register support, means controlled by the columnar-printing control means and controlling the movements of said movable means away from normal position as the columnar-printing control means moves from columnar position to columnar position, and means controlled by the register support as the latter moves and controlling the movements of said movable means toward its normal position.
- 10 13. A calculating machine having a traveling paper carriage, amount differential actuator mechanism, a register support, a plurality of registers carried by said register support, said register support being movable to select individual registers carried by said register support for cooperation with said differential actuator mechanism for performing calculating operations, a means movable away from and back to a normal position, means controlled by the paper carriage and determining the movements of said movable means away from normal position as the paper carriage tabulates, means controlled by the register support as the latter moves and determining the movements of said movable means toward its normal position, and means controlled by said movable means to release said register support for movement when said movable means is out of normal position and to arrest the register support while said movable means is in its normal position.
- 15 14. A calculating machine having a traveling paper carriage, amount differential actuator mechanism, a register support, a plurality of registers carried by said register support, said register support being movable to select individual registers carried by said register support for cooperation with said differential actuator mechanism for performing calculating operations, an escapement mechanism controlling the register selecting movements of said register support, said escapement mechanism including two movably mounted elements, namely a ratchet member and an escapement pawl, means controlled by the traveling paper carriage and acting on one of said elements to advance both elements, means controlled by the register support to operate the other of said elements to cause it to return toward its initial position in response to register selecting movement of the register support, and means controlled by the latter element to arrest the register support while said latter element is in its initial position and release said register support for register selecting movement while said latter element is out of its initial position.
- 20 15. A calculating machine having a columnar-printing control means, amount differential actuator mechanism, a register support, a plurality of registers carried by said register support, said register support being movable to select individual registers carried by said register support for cooperation with said differential actuator mechanism for performing calculating operations, a means movable away from a normal position to cause release of said register support for movement and also movable back to said normal position to cause arrest of the register support, means controlled by the columnar-printing control means moves from columnar position to columnar position, means for moving said columnar-printing-control means through a plurality of columnar positions in a continuous movement, means controlled by the register support as the latter moves and controlling the movements of said movable means toward its normal position, and means controlled by said movable means to release said register support for movement when said movable means is out of normal position and to arrest the register support while said movable means is in its normal position.
- 25 16. A calculating machine having a traveling paper carriage, amount differential actuator mechanism, a register support, a plurality of registers carried by said register support, said register support being movable to select individual registers carried by said register support for cooperation with said differential actuator mechanism for performing calculating operations, a means movable away from and back to a normal position, control means connected with the paper carriage, said control means comprising a control element for each of a plurality of control positions of the paper carriage, said control means also controlling the movements of said movable means away from normal position as the paper carriage tabulates through each position for which a control element is provided, means for moving said carriage through a plurality of its control positions in a continuous movement, means controlled by the register support as the latter moves and controlling the movements of said movable means toward its normal position, and means controlled by said movable means to release said register support for movement when said movable means is out of normal position and to arrest the register support while said movable means is in its normal position.
- 30 17. A calculating machine having a traveling paper carriage, a register support, a plurality of registers on said support, a detent for said support, a ratchet, means carried by said carriage for rotating said ratchet, a pawl holding said ratchet against return rotation, a second ratchet rotating with the first ratchet, a second pawl moved away from a normal position by the second ratchet as it rotates, means controlled by the register support to operate said second pawl to release it for movement in the return direction relatively to said ratchets and under control of said last named means, and means controlled by said second pawl for operating said detent to release the register support as said second pawl moves out of normal position and to arrest the register support as said second pawl returns to normal position.
- 35 18. A calculating machine having a traveling paper carriage, a number of registers on a register support movable to a corresponding number of register selecting positions from a first register selecting position to a last register selecting position, register selecting means set-

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

table by said carriage as the latter moves from column to column to select predetermined registers in accordance with the positions to which said carriage moves, said register selecting means being set into operation to initiate movement of said register support as the carriage moves and continuing to operate after the carriage stops to complete the movement of the register support in accordance with the register selected, and means for preventing further setting of said register selecting means by the traveling paper carriage when the register support reaches its last register selecting position.

19. In a calculating machine, columnar-printing-control means, a movable register support, a plurality of registers on said support, and register selecting means comprising an escapement mechanism having portions normally restraining said register support from movement but movable by said columnar-printing-control means to release said register support for movement, and portions operable by said register support upon movement thereof to restore said restraining portions to restraining condition. 5

ARTHUR J. FETTIG.
